BATTERY PACK FOR A MOTOR-DRIVEN CAMERA

Hugo L. Wessels, Miami, Fla.

Filed Sept. 1, 1964, Ser. No. 81,545

Term of patent 7 years

(Cl. D61—1)

FIG. 1 is a perspective view taken from the front left corner of a battery pack for a motor-driven camera showing my new design;

FIG. 2 is a plan view thereof;

FIG. 3 is a bottom view thereof;

FIG. 4 is a right-end view thereof; and

FIG. 5 is a rear view thereof.

The broken-line showing of a partial camera body and lens barrel are for illustrative purposes only.

I claim:

The ornamental design for a battery pack for a motor-driven camera, substantially as shown and described.
